UNITED STATES PATENT OFFICE.

CHARLIE W. ANTHES, OF AMHERST, NEBRASKA.

WASHING-MACHINE.

1,210,395.

Specification of Letters Patent.

Patented Jan. 2, 1917.

Application filed July 7, 1915. Serial No. 38,537.

To all whom it may concern:

Be it known that I, CHARLIE W. ANTHES, a citizen of the United States, residing at Amherst, in the county of Buffalo, State of Nebraska, have invented certain new and useful Improvements in Washing-Machines; and I do hereby declare the following to be a full, clear, and exact description of the invention, such as will enable others skilled in the art to which it appertains to make and use the same.

This invention relates to new and useful improvements in washing machines particularly of that type including a rockable body portion which is provided with suitable compartments wherein air and water are adapted to be imprisoned upon rocking the body in one direction and released upon rocking it in the other direction to provide sufficient agitation of the clothes and water in the body to properly wash said clothes.

It is in general the object of the present invention to improve and simplify the structure and efficiency of machines of this character, and it is more specifically the object of the present invention to provide means within the body wherein when it is rocked in one direction water will be caught and held so that when it is rocked in the other direction the water thus held will be elevated and then poured down upon the clothes in the body to properly agitate the clothes and promote the circulation of water through the machine, this means being used in connection with air imprisonment and releasing means for releasing air under the clothes.

With the above and other objects and advantages in view, the invention resides more particularly in the novel combination, formation and arrangement of parts as more fully described hereinafter and pointed out in the appended claims.

Reference is had to the accompanying drawings, wherein similar characters of reference designate corresponding parts throughout the several views, and in which:

Figure 1 is a vertical sectional view taken in a plane at right angles to the axis of the body. Fig. 2 is a vertical sectional view taken in a plane including the axis of the machine. Fig. 3 is a perspective view of one of the water holding receptacles.

Referring now more particularly to the accompanying drawings there is shown a body portion including substantially semi-circular sides 5 and the bottom 6 which is

curved to provide the ends of the body. A cover 7 is provided for the body and has a central opening 8, the sides of the cover being inclined downwardly toward this opening to provide proper drainage and the cover being secured to the sides and ends of the body above their top edges to provide a drainage pan for use should it be desired to mount a wringer on the supporting body of the frame. To prevent spilling of water from this drainage pan upon rocking the body the upper edges of the ends are turned inwardly as at 8'. The frame for rockingly mounting this body comprises supports 9 of inverted U-shape at the sides of the body and having their legs connected by the cross braces 10 and carrying on their bights bearings 11 which pivotally receive pintles 12 projecting from the upper central portions 75 of the sides 5 of the body. The body is preferably braced by strips 13 secured to its sides and extending radially from the said pintles. For rocking the body a handle 14 is secured to one of the sides and extends 80 thereabove.

A wringer structure is provided and comprises a spaced pair of bars 15 secured to the bight portion of the support 9 and to a brace 16 connecting the legs of said support 85 and the upper ends of these bars carry a wringer mechanism 17 which is disposed over the opening 8 so that as the clothes are taken out of the body of the machine they may be wrung and the water permitted to 90 flow back into the body.

The bottom and ends of the body are curved to merge into each other and secured to the lower portions of the ends and adjacent portions of the sides are plates 18 which 95 extend at an angle to the bottom and form therewith pockets, the top planes of which are inclined at an acute angle to the horizontal so that upon rocking the body air will be imprisoned in these pockets and released 100 upon rocking of the body in the other direction at a time when the clothes and water have dropped over said pockets so that the air thus released passes upwardly through the clothes and water and agitates them to 105 effect a cleansing action. Further agitation is effected by the provision of water holding members 19 which are positioned in the upper end portions of the body and comprise each an outer wall substantially vertical and spaced inwardly from the end of the body and an inner wall extending at an

angle of substantially forty-five degrees to form a substantially V-shaped cross section. The intermediate portions of these water holding members 19 are braced by U-shaped 5 braces 20 having their ends embracing said members and secured to the sides thereof and having their bights secured to the ends of the body adjacent the plates 18. Thus as the body is rocked to depress one end thereof 10 water flows into the receptacle at that end. As the body is tilted back to depress the other end and consequently raise the first end the water flows from the water holding members onto the clothes and causes a subsequent agitation. Provision of these water 15 holding members also conduces to a greater circulation of water in the body in that when the body is rocked, the clothes lodge between the member and the end of the body and 20 are thus held while the water flows past and into the member.

While I have illustrated and described a particular embodiment of my invention, I have merely done so for the sake of convenience and I do not wish to be limited to that particular embodiment as it is obvious that numerous changes may be made within the details of construction thereof without in any way departing from the spirit of the 25 invention or exceeding the scope of the appended claims.

What I claim is:

1. In a washing machine of the class described, the combination with a supporting 25 frame, of an oscillatory clothes receptacle mounted therein having a rounded bottom, a

cover for the receptacle, laterally extending arcuate plates disposed on opposite sides of the said bottom and each having their upper edges secured to the bottom, the body portion 40 of each of said plates being curved inwardly, outwardly and downwardly with respect to the receptacle bottom to provide air pockets, substantially V-shaped laterally extending plates arranged above said air pockets and 45 spaced from the end walls of the receptacle, and supporting braces for the said V-shaped plates mounted upon the arcuate plates whereby when the receptacle is rocked in one direction, water may pass up between the 50 arcuate plate and the V-shaped plate above to be deflected into the latter by the end wall and cover of the receptacle.

2. In a washing machine of the class described, the combination with a supporting frame, of an oscillatory clothes receptacle mounted therein having a rounded bottom, a cover for the receptacle, laterally extending arcuate plates disposed on opposite sides of the said bottom to provide downwardly 55 opening air pockets, substantially V-shaped laterally extending plates arranged above said air pockets and spaced from the end walls of the receptacle and from said arcuate plates.

In testimony whereof, I affix my signature, in the presence of two witnesses.

CHARLIE W. ANTHES.
